CLAIM

The ornamental design for a glove for playing with a cat, as shown and described.

DESCRIPTION

FIG. 1 is a perspective top and front view of a glove for playing with a cat showing my new design;

FIG. 2 is a front view of FIG. 1;

FIG. 3 is a top view thereof;

FIG. 4 is a right side view thereof;

FIG. 5 is a rear view thereof;

FIG. 6 is a bottom view thereof; and,

FIG. 7 is a left side view thereof.

The broken-line disclosure of a kitten and part of an arm in FIG. 1 is for illustrative purposes only and forms no part of the claimed design.

1 Claim, 2 Drawing SheetsFIG. 5.*FIG. 6.*FIG. 7.
